INSERTION FOR TOBACCO PIPES

Claes Axel Klingenstierna, Karlstad, Sweden

Application January 3, 1939, Serial No. 249,093
In Sweden February 2, 1938

9 Claims. (Cl. 131—183)

Due to the fact in tobacco pipes that the opening of the channel in the pipe stem lies asymmetrically in the bottom of the bowl, the combustion of the tobacco in the pipe bowl proceeds unevenly so that the glowing surface of the burning tobacco lies obliquely in the bowl.

The chief object of this invention is to remove such draw back and to cause the combustion of the tobacco to take place uniformly over the whole surface of the burning tobacco. Thus, the glowing surface of the tobacco will be parallel with a plane through the upper free edge of the pipe bowl, and will not become oblique.

Another object of this invention is to provide an insertion element which will effect an efficient deposition and condensation of oil within the insertion and also on the bottom of the cavity in the pipe bowl below the insertion.

Another object of this invention is to create a strong circulation of the smoke within the tobacco and in the cavity of the pipe bowl, so as to effect an efficient air-drying of the insertion device and of the said cavity in the pipe bowl both during the smoking and thereafter.

Other objects of the invention will be evident from the following specification and claims.

One embodiment of an insertion in accordance with this invention is shown in the annexed drawing.

Fig. 1 shows an insertion device in accordance with this invention, as developed in a plane.

Fig. 2 shows a vertical section through a pipe bowl with the insertion device in its proper place.

Fig. 3 shows a plan view of the insertion device and the pipe bowl shown in Fig. 2.

Fig. 4 shows the insertion separately, as seen from the right in Fig. 2 or 3.

Fig. 5 is a bottom view of the insertion device.

Fig. 1 is on a smaller scale. Figs. 2-5 are on the same, larger scale.

Referring now to the drawing, it may first be mentioned that the insert device is preferably made of one integral piece of sheet metal, punched to the shape shown in Fig. 1. Thus, the insertion has a central unbroken portion 1, which is to be bent to form a cylinder or a truncated cone. At the upper edge thereof a number of flaps or arms 2-8 are provided, and one flap 5 is longer than the other flaps. At the lower end of the portion 1, there are three shorter flaps 9, 10, 11 and between them interstices or recesses 12, 13.

The upper flaps 2, 4, 6, 8 are bent inwards to form a bottom or combustion grate having holes 14, 15, 16 at the remaining upright flaps or arms

3, 5, 7. Preferably, the arms 3 and 7 are bent to a concave shape, adapted to the wall of the cavity in the pipe bowl 17. Also the flap 5 may be bent to a concave shape, though as a rule, this is not necessary. The flaps 9 and 10 are bent slightly inwards for adapting them to the shape of the concavity in the pipe bowl. The flap 11 is bent still more inwards and may even be bent inwards substantially at right angles with the portion 1, as shown in Figs. 2 and 5. It is to be observed that the interstice 12 between the flaps 9 and 10 is substantially rectangular, while in the interstice 13 the two opposite sides or edges are not parallel but form an angle with each other. In other words the flap 10 is bevelled on one side.

When the insertion is inserted into the pipe bowl, the flap 5 should be placed next to the pipe stem. Preferably, the flap 5 is bent round the upper edge of the pipe bowl, as shown in the drawing. In this position of the insertion, the interstice 12 is just in front of the channel in the pipe stem and the flaps 9, 10 are on both sides on this channel. Due to the distribution of the draught thus effected—and this distribution is substantially affected by the flap 11 bent inwards—an even combustion across the whole upper surface of the tobacco is attained, and simultaneously oil is deposited on the lower flaps 9, 10, 11 and on the bottom of the cavity of the pipe bowl. Furthermore, a good circulation of the smoke through the tobacco is attained, and air is circulated for drying the insertion and the cavity of the pipe bowl.

It might be mentioned that an even, uniform combustion is attained, even if the insertion is turned 180° from the position shown in Figs. 2 and 3 so that the arm 5 is diametrically opposite to the channel in the pipe stem. In this case, the condensation of oil is somewhat less, and the circulation of air for drying is not so strong.

The flaps 3, 5, 7 conduct the heat and thus effect an increased drying of the insertion. By means of the arms 3, 5, 7 the insertion is inserted into the pipe and removed therefrom. Due to their concave shape the arms 3, 5, 7 are more rigid than they would be otherwise and for the same reason the holes 14, 15, 16 of the grate are bigger. It may be mentioned that it is not necessary to bend the arm 5 over the upper edge of the pipe bowl, but it may be bent down to engage the opposite wall of the pipe bowl; the arm 5 serving then as a kind of spring pawl for keeping the insertion in its place in the pipe. In such case, the hole 15 will not be closed, but the arm 5 bent

down protects that hole from being obturated by tobacco flakes or the like. By bending the flaps 2, 4, 6, 8 suitably, the combustion grate may be made plane, concave or convex. Because the two edges of the portion 1 overlap at 18, the insertion may adapt itself by spring action to pipe bowls having different inside diameters, and in such case the holes in the combustion grate will remain substantially constant due to the width of the upright flaps 3, 5, 7, independently of the reduction or increase of the diameter of the portion 1, within practical limits.

It may be mentioned that the flaps 9, 10, 11 may be removed and that the cone may then be extended downwards and may be provided with a small central hole in the bottom. It is also possible to arrange other small holes around a central bottom hole. The combustion grate may consist of a round piece of perforated sheet metal or the like, but the embodiment shown is preferred, both with regard to its manufacture and its action. It is essential that the flaps 9, 10 and 11 be correctly placed in relation to the large holes 14, 15, 16, for attaining a correct distribution of the draught, an even and uniform combustion and a good deposition of oil. The condensation of oil may be controlled by bending the flap 11 inwards to different angles. If this flap points vertically downwards, the condensation of oil has a minimum value; but nevertheless the combustion is even and uniform. When the flap 11 is bent at right angles to the portion 1, the best condensing action is attained, including a very strong condensation of oil on the bottom of the insertion, and a minimum of condensation on the bottom of the pipe bowl. This facilitates the cleansing very much.

What I claim is:

1. In an insertion adapted to be inserted into a tobacco pipe bowl, a bottom having holes for carrying the tobacco and forming a grate, an extension below said bottom, said extension being substantially circular in cross-section, and draught-distributing means in the lowermost part of said extension.

2. In an insertion adapted to be inserted into a tobacco pipe bowl, a bottom having holes for carrying the tobacco and forming a grate, a substantially cylindrical extension below said bottom, and draught-distributing means in the lowermost part of said extension.

3. In an insertion for the bowl of a tobacco pipe, a perforated bottom for carrying the tobacco and forming a grate, an extension below said bottom, said extension having substantially the shape of a truncated cone, and draught-distributing means at the lowermost part of said extension.

4. In an insertion adapted to be inserted into a tobacco pipe bowl, a bottom having holes for supporting the tobacco and forming a grate, an extension below said bottom, said extension being substantially circular in horizontal cross-section, and downwardly directed flaps at the lower edge of said extension for directing the draught.

5. In an insertion for the bowl of a tobacco pipe, a body piece substantially circular in horizontal cross-section, flaps at the upper end of said body bent downwards to form a bottom having holes between said flaps, other upright flaps at the upper edge of said body, and air-current distributing means at the lower end of said body.

6. In an insertion adapted to be inserted into the bowl of a tobacco pipe, a sheet metal member in the form of a truncated cone cut along a generatrix and having overlapping edges, a plurality of flaps at the upper end of said sheet member, each alternate one of said flaps being bent inwards to form a bottom having holes for carrying the tobacco, each of the others of said flaps being upright and bent to a concave shape substantially conforming to the shape of the inner side of said pipe bowl, and downwardly directed flaps at the lower edge of said sheet member.

7. In an insertion adapted to be inserted into the bowl of a tobacco pipe, a sheet metal member in the form of a truncated cone cut along a generatrix and having overlapping edges, a plurality of flaps at the upper edge of said sheet member, each alternate one of said flaps being bent inwards to form a bottom for carrying the tobacco, said bottom being provided with holes therethrough, each of the others of said flaps being upright and bent to a concave shape substantially conforming to the inner surface of said pipe bowl, one of said upright flaps being longer than the others, and two flaps at the lower edge of said sheet member spaced apart so as to leave an interstice at said lower edge vertically below said long upright flap.

8. In an insertion adapted to be inserted into the bowl of a tobacco pipe, a sheet metal member in the form of a truncated cone cut along a generatrix and having overlapping edges, a plurality of flaps at the upper end of said sheet member, each alternate one of said flaps being bent inwards to form a bottom having holes for carrying the tobacco, while each of the others of said flaps is upright and bent to a concave shape substantially conforming to the shape of the inner surface of said pipe bowl, and one of said upright flaps being longer than the others, two flaps at the lower edge of said sheet member and spaced apart so as to leave an interstice at said lower edge vertically below said long upright flap, and an additional flap at said lower edge of the cone, said additional flap being bent inwards substantially at right angles to the outer surface of said sheet member.

9. In an insertion adapted to be inserted into the bowl of a tobacco pipe, a sheet metal member in the form of a truncated cone cut along a generatrix and having overlapping edges, a plurality of flaps at the upper end of said sheet member, each alternate one of said flaps being bent inwards to form a bottom having holes for carrying the tobacco, while each of the others of said flaps is upright and bent to a concave shape substantially conforming to the shape of the inner side of said pipe bowl, and one of said upright flaps being longer than the others, two flaps at the lower edge of said sheet member spaced apart and leaving an interstice at said lower edge vertically below said long upright flap, and an additional flap at said lower edge of the sheet member between said two flaps, said additional flap being bent inwards substantially at right angles to the surface of said sheet member, the edges of said two flaps at the lower edge of said cone which are next to said additional flap being bevelled.
